RAZOR

Emile Gagnan, Montreal, Quebec, Canada

Application October 16, 1951, Serial No. 251,472

Claims priority, application France January 16, 1951

11 Claims. (Cl. 30—43)

The present invention relates to a razor to be operated manually without the use of an electric motor or other driving means.

A few razors of this general type have already made their appearance but their low efficiency is such that they cannot be compared to electric razors.

These razors include cutting means placed behind a perforated screen which is applied to the skin.

Generally, they comprise a drum which rolls on the skin over cutting means. No special means are usually provided to guard the lateral edges of the drum while still leaving it flexible enough for very good contact with the cutting means and yet protect the skin from the edges of the drum which is sharp, particularly when the screen is thin. Generally speaking, however, most such razors embody a drum having end rings for actuation, reinforcing or skin-protecting purposes.

Furthermore, these devices use a perforated drum which has an endless continuous surface and thus are hard and expensive to manufacture.

In some apparatus with an alternating movement, this inconvenience has been remedied by using a free flat flexible screen under a rigid frame. The efficiency of this type of razor is relatively low because of the limited movement possible.

The present invention has been conceived to overcome the disadvantages noted above and, thus, its primary object may be stated to reside in the provision of a razor of the character described which is efficient and an improvement in the art of mechanical razors, or dry shavers.

Another important objective of the invention is the provision of a shaver of the character described which is operable to function in a continuous movement, or in relatively lengthy alternating motions.

A further object concerns a manually operated shaver embodying a perfectly free perforated screen, quite thin, and fully protected so as to prevent cutting the skin of the user.

Still an important object contemplates a shaver so constructed that dismantling and cleaning can be easily and quickly effectuated for optimum sanitation.

Another object envisages a shaver of the character described which is inexpensive and yet rugged and of long life expectancy.

Other objects and advantages of the invention will be pointed out further, or become apparent, during the description to follow.

The present invention is embodied in a razor having the following basic characteristic. It includes a fixed body on which blades are mounted. A curved flexible band-like screen or grill is mounted to surround the body completely, or substantially completely, and to ride on the edges of the blades. On at least one side of the body is mounted a lateral guard which extends above and overlaps the edge of the screen to provide a sliding space between the guard and the body, in which space the edge of the screen is adapted to move.

As an example, and for purposes of illustration only, an embodiment of the invention is shown in the annexed drawing, wherein:

Figure 1 is a perspective view of the razor, or shaver, in operative position;

Figure 2 is another perspective view of the razor but with its cover in partly-removed position;

Figure 3 is a perspective view of the constitutive elements of the shaver, in their approximate relative position and shown in the so-called "exploded" manner;

Figure 4 is a vertical section transversely through the medial portion of the razor, such as along line 4—4 of Figure 1;

Figure 5 is a side elevation of the razor, shown with the side plate removed, and

2

Figure 6 is a perspective view of a razor basically the same as in Figure 1 but in which the screen moves in a circular path instead of the oval path of Figure 1.

Referring, now, to the drawing wherein similar reference characters represent corresponding parts throughout, the numeral 10 generally designates the composite body of the shaver, which body is constituted of parallel, spaced plates 11 having holes for mounting over supporting rods 13. The correct spacing between the plates is achieved by spacers, or sleeves, 14 press-fitted over the rods and between the plates. Thus, a rigid unit is provided for holding angularly inclined cutting blades 15 mounted in slots 16 cut in the upper portion of the plates. (See Figures 3, 4 and 5.) Although the body 10 has been shown in Figure 3 as a composite, it is clear that it may be made equally well in solid form. As a matter of fact, this is exactly the type of body shown in Figure 6.

The blades 15 have one cutting edge only and, actually, are razor blades presently available on the open market. Said blades are positioned in the slots so that their cutting edges are perpendicular with the sides of the body, or plates 11 thereof in Figure 3, whereby a supporting area is constituted over which the flexible screen will be displaced.

The screen 20 is a thin closely perforated strip adapted to surround the body completely, and to ride over the blades 15. In practice, said screen may be made of steel and preformed to assume the natural shape shown in Figure 3, that is: the general configuration is curved, the meeting ends being given a roll inwardly for better contact together and the blades when in overlapped position. Said ends may be skewed, also, as shown in Figure 1.

The sliding path of the screen, around the body and blades is defined by side cheeks, or plates, 21 slightly larger than the body 10 with mounted blades, or plates thereof, one of said cheeks being permanently secured to one end of the rods 13, by riveting at 22 for instance, said fixed cheek being spaced from the adjacent plate 11 by spacers 14. The other cheek is removable, for dismantling the shaver and, for that purpose, is simply held in place at the ends of the rods 13 fitting in the holes 12 of removable cheek 21 (Figure 3). Spacers 14 are used also to position the removable cheek 21 with respect to the body 10 and maintain, between both cheeks, the proper spacing necessary for free running of the screen edges around the body.

It is again noted at this juncture that the main characteristic of the invention resides in this free running of a thin perforated screen loosely around a body and between lateral cheeks, the side edges of said screen being additionally guided along a proper path around said body by means of a guard flange on the edge of the cheeks.

Such a flange 25 is clearly shown in Figures 3 and 4, formed right-angularly with respect to the plane of the cheeks and adapted to overlie the outer margins of the screen 20, parallel thereto and at a small distance therefrom. Consequently, between each flange and the body with blades there is defined, bounded by the side cheeks, a track or race in which the flexible, free, perforated screen is adapted to run around the body.

Said guard, therefore, has the dual function of guiding the screen as it freely moves and, also, protecting the skin of the user from contact with the sharp edges of the screen.

The shaver is completed by the addition of removable means for holding the removable cheek 21 in place; this may be accomplished by a cover such as the one designated 30 in Figures 3 and 4. This cover is shaped to conform with the body and carries side flanges 32 formed at the edges of the back 31. Said flanges are adapted to engage the side cheeks and, thus, hold the razor parts together. The engagement, of course, should be sufficiently snug for resiliently retaining the removable cheek in place when the razor is used and, yet, should be such as to permit easy disassembly for cleaning and other purposes.

If desired, also, apertures 35 may be made in the cover back 31, said apertures allowing passage of cut hair and, generally, for cleaning the razor by blowing

therethrough or wetting under the water tap. This wetting is obviously permissible if the shaver is made of stainless material.

The shaver shown in Figure 6 is a smaller embodiment of the invention in cylindrical arrangement, that is, the screen is displaced along a circular path around the body 40 and over the blades 45 secured at an angle therein. The side cheeks 41 are also circular and in the form of discs having the guard flanges 55. As described previously in connection with the guards 25, the circular guards 55 have no connection whatever with the screen 50 and, furthermore, are actually spaced from the body and blades to provide the guiding race for said screen. The cheeks 41 are axially apertured at 42 to be located concentrically with the body over shoulders 44 formed at the ends thereof.

The cheeks are held in movable, or fixed position, by the slotted arms 52 of a yoke 51, the slots of said arms fitting over the squared bosses 43 of the body 40. Except for the shape of the body and screen, the working principle and operation of the shaver of Figure 6 are the same as for the shaver of Figures 1 to 5.

In operation, the shaver is held between the thumb and fingers (the side cheeks 21 or arms 52 of the yoke) and the screen pressed on the parts to be shaved. A continuous, or alternating, movement imparted to the shaver will cause a corresponding movement of the blades under the screen which, in frictional contact with the parts to be shaved will be displaced relatively to the blades. It is the shearing action between said blades and the screen that severs the hairs penetrating through the perforations of the screen from the parts being shaved.

Obviously, the blades being inclined with respect to the plane of the screen, it is necessary that the ends of said screen be positioned properly relative to the blades. Otherwise, in one direction of movement the underlying end of the screen would catch under the blades; for preventing such an occurrence it is only necessary to overlap the edges in such a manner that said underlying end should point in the same direction as the blades. Thus, the leading edge of said end will slide over the inclined blades, in both directions, without encountering directly the knife edge of said blades and, hence, without possibility of catching thereunder.

As stated previously, the screen must be free to move over the blades and around the body; as a matter of fact this freedom of movement involves even a definite looseness, permitting the screen to lie flat over the blades area and, even, to adjust itself automatically to the small level differences that may exist between adjacent blades. Consequently, this feature of the free and loose screen, guided by its edges into a suitably shaped race is the improvement representing an advance of the art. In the opening paragraphs of this description it has been stated that the construction of previously suggested razors, or shavers, necessitated a cylindrical endless screen which is difficult and expensive to manufacture, that is: such a cylinder requires grinding and machining a tube into a suitably thin structure.

Obviously, such a continuous screen is perfectly adapted to be used with the shaver of the present invention, provided it is made loose enough to meet the objective noted, namely: freedom to be guided under protective guards. Naturally, however, there would be no point in using such a continuous screen because the cost of manufacture would be a deterrent.

The advantages of a shaver constructed as above described are many: first of all, it is an efficient device that, in practice, has proven that it can shave as close as any other mechanical razor. Furthermore, it can be made inexpensively and in almost any rounded shape desired. Even in small sizes, the shearing area can be made large enough to render practical a pocket and the like miniature devices.

Contrary to some razors having special shearing means, the shaver of the invention is not painful in use and, also, cannot cut, abrade or otherwise injure the skin of a user.

Finally, it can be taken apart, in a matter of seconds, for cleaning and parts replacement purposes. Summing up, consequently, the shaver of the invention is a body of suitable shape carrying inclined cutting blades and over which body and blades an enveloping perforated screen is freely mounted. For locating the screen with

respect to the body and blades, lateral side plates are provided which embody inwardly directed flanges, overlying the screen edges and spaced from the blades and body, for defining a race, or sliding space, in which the screen edges are located and protected.

Basically, therefore, the present invention is characterized by a flexible screen loosely mounted around a body carrying cutting blades, said screen being adapted to be displaced under lateral screen-edges-overlying guards.

It must be understood that various changes as to the shape, size and arrangement of parts can be resorted to without departing from the spirit of the invention or the scope of the subjoined claims.

I claim:

1. A razor of the type which includes a body, a number of blades mounted on the body, and a screen moveable relative to the body to shear whiskers penetrating the screen in which, the body includes means for supporting a plurality of blades, guards connected to the body and overlapping the lateral edges of the screen to form under the guards a sliding space for said edges of the screen, the screen being in the form of a curved band positioned about the body with its edges in said space and overlying said blade edges in a position to slide in contact therewith.

2. A razor, according to claim 1, in which the body comprises a solid block of material, and said block is cut away to provide blade receiving recesses.

3. A razor, according to claim 1, which includes a cover enclosing the body and guard assembly, said cover having an opening at least adjacent to said blades.

4. A razor, according to claim 1, in which the over-all form of the body is cylindrical.

5. A razor, according to claim 1, in which the over-all form of the body is cylindrical, the guard being rotatably mounted in relationship to the body.

6. A razor, according to claim 1, in which the body is substantially oval in over-all cross section.

7. A razor, according to claim 1, in which the screen is discontinuous and its ends overlap with the inside end facing the same direction as the cutting edges.

8. A razor, according to claim 1, in which the screen is discontinuous and its ends overlap with the inside end facing the same direction as the cutting edges, the overlapping ends being at an angle to the blades.

9. A razor of the type which includes a body, side guards secured to the body, and a number of blades mounted on the outside of the body and a convolute flexible screen surrounding the body and held between the guards and adapted for movement relative to the blades, the screen being discontinuous and having its disconnected opposite ends at least close together.

10. A shaving device, comprising, a body including means for holding a number of blades with their edges in substantially parallel relationship, a screen movable with respect to said blades, guards held to the body and having portions overlapping the edges of the screen to form between the blades and the guard a space for the movement of the screen.

11. In a shaver having a body provided with projecting cutting blades and a thin, flexible, perforated screen loosely and freely mounted to move around said body and over said blades, the improvement consisting in guiding and protecting the edges of the screen under side guards associated with the body, said side guards extending above and overlying the edges of said screen, thereby defining with the body and blades cutting edges a recessed race in which the screen is guided during its movement relative to the body.
